UNITED STATES PATENT OFFICE.

PIERCE X. JOHNSON, OF DENVER, COLORADO, ASSIGNOR, BY DIRECT AND MESNE ASSIGNMENTS, TO JOHNSON-BRADFORD SAFE COMPANY, A CORPORATION OF OREGON.

BURGLAR-PROOF SAFE.

1,026,207.

Specification of Letters Patent. Patented May 14, 1912.

Application filed February 3, 1911. Serial No. 606,312.

To all whom it may concern:

Be it known that I, PIERCE X. JOHNSON, a citizen of the United States, residing in the city and county of Denver and State of Colorado, have invented certain new and useful Improvements in Burglar-Proof Safes; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in safes, my object being to provide a safe which cannot be blown open.

The principle employed in my present invention consists in perforating the wall of the safe in such a manner that the force of an explosive cannot be sufficiently confined to seriously injure the safe.

I prefer to construct the wall of the safe of a number of members suitably spaced to 25 form intervening air chambers, each member being perforated, the perforations of the adjacent members being staggered.

As illustrated in the drawing the wall is composed of three members, the material employed being preferably manganese steel, which is so hard that it is practically impossible to drill, bore or otherwise mutilate it by the usual instruments employed by safe burglars.

35 The perforations employed in connection with the walls of the safe are preferably elongated and relatively thin. By providing intervening air chambers, the nitroglycerin, the usual agent employed in blowing safes, is in liquid form and if injected through the narrow perforations of the outer wall, it will run downwardly in the air chamber adjacent the wall and either explode before any considerable amount has 40 collected, or will run out through other, perforations either in the lower part of the wall or in the bottom of the safe, which is also perforated.

Within the wall composed of the per-

forated members is located a fireproof lining or box which may be of ordinary construction.

Having briefly outlined my improved construction, I will proceed to describe the same in detail, reference being made to the accompanying drawing in which is illustrated an embodiment thereof.

In this drawing: Figure 1 is a vertical section taken through a safe equipped with my improvements. This section is taken 60 through the safe on a plane parallel with the door when the latter is closed, the section being indicated on the line 1—1, Fig. 2. Fig. 2 is a horizontal section taken through the safe on the line 2—2, Fig. 1. 65 Fig. 3 is an inside view of the door, two of the three wall members of which the door is composed being partly broken away to disclose the outer member. Fig. 4 is a perspective view of my improved safe. Fig. 5 70 is a perspective view in detail of a spacing bar employed in connection with the separated telescoping members of my improved safe.

The same reference characters indicate the 75 same parts in all the views.

Let the numerals 5, 6 and 7 respectively designate three wall members of a safe, the said members constituting the top, bottom, sides and rear walls of the safe, in other 80 words, form a complete inclosure except in front where the door 8 is employed.

The numeral 5 designates the outermost member of the wall; the numeral 6 the intermediate member; and the numeral 7 the 85 innermost member. Each of these members is provided with perforations 9 which may be of any suitable formation. I prefer that they consist of narrow elongated openings and that they be sufficiently numerous to 90 make it impossible to sufficiently confine explosive force within or between the wall members, to seriously injure the safe by the use of the high explosives ordinarily employed for this purpose.

As illustrated in the drawing the wall members are separated by spaces 10, a similar space 12 being left between the inner-

most perforated wall member and the fireproof box or lining 13.

The wall members may be spaced in any suitable manner. As illustrated in the drawing 5 angle-shaped spacers 14 are employed, both for spacing the perforated wall members and also for spacing the innermost perforated wall member from the fireproof box or lining. These spacers may be either continuous 10 from the front to the rear of the safe, or they may be broken or separated, whereby an explosive introduced into the spaces between the wall members may pass downwardly and out at the bottom of the safe through the perforations formed therein.

As illustrated in the drawing it is assumed that the wall members are made complete and of manganese steel. In assembling 20 the said members, the spacers 14 are placed in the lowermost corners of the outermost member 5. The member 6 is then inserted, being moved from the front rearwardly, its corners engaging counterpart recesses 25 in the spacers 14. This member is pushed rearwardly as far as it will go. Spacers 14 are then put in position in the lower corners of the member 6, after which the member 7 is moved into place in the same 30 manner; and finally the other spacers 14 are placed in position in engagement with the member 7, after which the fireproof box or lining 13 is inserted.

The door is hinged to the outer wall member 35 of the safe as shown at 15. This door as illustrated in the drawing is composed of three members to harmonize with the members 5, 6 and 7 constituting the top, bottom, side and rear walls of the safe as heretofore explained. These members of the door 40 are respectively designated 16, 17 and 18, 16 being the outer member, 17 the intermediate member and 18 the innermost member. The area of these members diminishes as 45 they extend inwardly, and their edges are beveled to fit correspondingly beveled edges formed on the wall members of the safe. For instance, the vertical edges of the wall members 5, 6 and 7 extend inwardly as 50 shown at 19, 20 and 21, to form shoulders adapted to be engaged by the outer extremities of locking bolts or bars 22 which are located in spaces 23 and 24 left between the members 16 and 17 of the door. These bars 55 22 engage lugs 25 which are recessed to receive the bars, the lugs thus forming guides for the said bars. The inner extremities of these bars are enlarged, these enlargements being provided with openings 26, which as 60 illustrated in the drawing are somewhat elongated in a vertical direction. Through these openings of each pair of bars 22 is passed a manipulating spindle 27 having cam projections 28, one of said projections

being adapted to engage the enlarged inner 65 extremity of one bar 22, and the other cam the corresponding inner extremity of the other bar 22. These cams are oppositely disposed so that as the spindle is rotated the bars are moved in opposite directions. 70 That is to say, both bars are either thrown outwardly into engagement with the shoulders 19 and 20 of the wall members 5 and 6, or drawn inwardly whereby they are disengaged from said shoulders, depending 75 upon whether it is desired to open or lock the door of the safe. As illustrated in the drawing there are two spindles 27, each of which is employed to manipulate two sets of bars 22, one set being interposed between 80 the outer and intermediate members of the door, while the other set is interposed between the intermediate and innermost door members.

Each spindle 27 is suitably journaled in 85 the door of the safe, whereby it may be employed to manipulate the locking bars. The door members are further connected by projections 29 formed on the outermost member and protruding through openings 90 formed in the other two members of the door. These projections are surrounded intermediate the door members by spacing washers 30. The inner extremities of these projections protrude beyond the innermost 95 member of the door and are provided with openings 31 adapted to receive locking keys, whereby the door members are properly maintained in the assembled relation.

The outer extremity of each spindle 27 is 100 shouldered as shown at 32 and provided with a hand manipulating knob 33; while its inner extremity is equipped with a retaining key 34.

In order to space the wall members of the 105 safe in the rear, the spacing bars 14 are provided with rearwardly located shoulders 4, these shoulders being located far enough from the wall member against which the bar abuts, to properly space the wall members, 110 at the back of the safe. It will be understood that as the telescoping members are put in place, they cannot be moved rearwardly beyond the shoulders 4 of the spacing bars 14.

Having thus described my invention, what I claim is:

1. A safe whose walls are composed of a number of telescoping members suitably spaced and perforated, for the purpose set 120 forth.

2. A safe having a wall composed of a plurality of perforated members arranged in parallel relation and separated by air spaces, for the purpose set forth.

3. A safe having a plurality of walls, each provided with a multiplicity of narrow slots, for the purpose set forth.

4. A safe having a wall composed of a number of members separated by air spaces, each member being provided with a multiplicity of narrow slots, for the purpose set forth.

5. A safe whose walls are composed of a plurality of telescoping members suitably spaced and provided with perforations, the perforations of adjacent members being ar-

ranged in staggered relation, substantially 10 as described.

In testimony whereof I affix my signature in presence of two witnesses.

PIERCE X. JOHNSON.
